US0D1109902S

(12) **United States Design Patent** (10) Patent No.: **US D1,109,902 S**
(45) Date of Patent: ** Jan. 20, 2026

(54) **MOTION SENSOR NIGHT LIGHT**

(71) Applicant: **XiaMen Feipin Electronic Technology Co., LTD.**, Xiamen (CN)

(72) Inventor: **Kangsheng Xia**, Xiamen (CN)

(**) Term: **15 Years**

(21) Appl. No.: **29/935,911**

(22) Filed: **Apr. 4, 2024**

(51) LOC (15) Cl. **26-05**

(52) U.S. Cl.

USPC **D26/51**; D26/72

(58) **Field of Classification Search**

USPC D26/24, 26, 37, 60, 1, 2, 72, 51

(57) **CLAIM**

The ornamental design for a motion sensor night light, as shown and described.

DESCRIPTION

FIG. 1 is a front perspective view of a motion sensor night light, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the motion sensor night light, which form no part of the claimed design.

1 Claim, 8 Drawing Sheets
